MINERAL SEPARATOR

Charles Koch, Casper, Wyo.

Application May 19, 1930, Serial No. 453,743

Renewed June 27, 1933

6 Claims. (Cl. 209—44)

This invention relates to improvements in devices for recovering minerals by the process of washing.

The primary object of the present mineral recovering device is to catch or recover a larger percentage of the desired minerals than is possible with machines of the character at present in use and with less cost.

The present invention contemplates broadly the provision of a series of superposed troughs each disposed at an inclination and each emptying its contents into the next lower trough. All of these troughs are mounted for oscillation in a plane at right angles to the direction of flow of the minerals and wash water passing therethrough and each is provided with a means for separating the finer aggregate of the mineral from the coarser.

A further object of the invention is to provide in oscillating troughs of the above described character an improved form of agitator for each trough whereby the material being washed is thoroughly stirred up in each trough before its passage to the next lower trough.

Still another object of the invention is to provide in troughs of the above described character, an improved means for preventing the minerals from being raised to the top of the wash water as the same is discharged from one trough into the other and an improved means for making the flow of water in the troughs smooth and free of foam.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 is a view in top plan of the mineral separator embodying the present invention.

Figure 2 is a view in side elevation of the same.

Figure 3 is a view in longitudinal section of one of the troughs of the separator.

Figure 4 is a view in cross-section of the trough taken on the line 4—4 of Figure 3.

Figure 5 is a view in cross-section of the trough taken on the line 5—5 of Figure 3.

Figure 6 is a view in top plan of the forward end of one of the troughs.

Figure 7 is a front view of the upper portion of the supporting frame.

Referring more particularly to the drawings wherein like numerals of reference indicate corresponding parts throughout the several views, there is indicated generally by the numeral 1 a supporting framework for my improved mineral recovering machine which, as shown, consists of a pair or more of spaced parallel base beams 2 of suitable size and weight which extend transversely of the structure and spaced substantially parallel reinforcing base beams 3 which extend along and form the sides of the framework structure as shown.

At the four corners of the rectangular frame which is formed by the base beams 2 and 3 there are fixed upright beams 4 which are connected at their upper ends by head beams 5 and 6 which define a rectangle of the same size as that formed by the base beams 2 and 3.

Each of the head beams 6 has pivotally attached thereto, adjacent each end, a pair of depending hanger straps 7, the members of each pair being disposed upon opposite sides of the adjacent head beam in the manner shown in Figure 1. Pivotally secured as at 8 between the free ends of each pair of hanger straps 7 is a hanging beam 9 and the beams 9 suspended from each head beam 6 are connected by cross bars 10, the bars 10 connecting one pair of hanger beams being disposed at different elevations from the corresponding bars of the adjacent hanger beams.

Disposed between the hanger beams 9 of each pair and connecting one pair with the other is a series of troughs each of which is indicated generally by the numeral 11. As shown, these troughs rest upon the cross bars 10 of the hanger beams and due to the manner in which the cross bars 10 are disposed one trough is oppositely inclined to the next higher or next lower trough and as shown they are so positioned that each discharges into the raised end of the next lower one.

Each trough has a pair of side walls 12, a front and a rear wall 13 and 14 respectively and a bottom 15. The bottom 15 of each trough is formed to provide a number of transverse openings or recesses 16, one thereof being directly adjacent the rear wall of the trough and being of materially greater width than the others. This latter recess is indicated generally by the numeral 16a.

Each trough has in the bottom thereof a metal pan 17, the bottom of which is formed to provide a number of riffles 18 each of which positions

in one of the recesses 16. At its rear end the pan 17 is formed to provide a wide transverse trough 19 which positions in the recess 16a and the adjacent end of the pan is open and overlies the cut out portion of the rear wall 14 of the trough so that the contents of the trough may flow freely from the pan through this open end.

Within each of the pans 17 there is disposed over the bottom thereof and spaced approximately one-eighth of an inch therefrom a creeper 20 of canvas, burlap, or other flexible material, the sides and front end edges of which are turned to extend up over the inner faces of the adjacent side and front end walls of the trough in the manner indicated at 21.

The turned up end of the creeper 21 at the front end of the trough is secured in place by a dash plate 22 but is disposed transversely across the front end of the trough and extends a substantial distance upwardly beyond the top thereof as shown.

Extending longitudinally of the inner face of each side wall 12 of each trough is an upwardly and inwardly directed water guide board 23 the lower edge of which overlies the adjacent turned up side edge of the fabric creeper 20 and secures the same in place.

In the rear end of each trough there is disposed an upright frame which is indicated generally by the numeral 24. This frame is of substantially U-shaped configuration and has each upright arm 25 thereof bolted or otherwise secured to the adjacent side 12 of the trough. The lower portion 26 of the frame is provided in its upper face with a longitudinal recess 27 in which snugly fits a pair of plates 28 which have clamped between them the forward edge of the fabric creeper 20. From this it will be seen that the forward edge of the creeper 20 turns downwardly slightly into the transverse mineral receiving trough 19 of each trough pan and is held in spaced relation by the supporting frame 24 to the adjacent side of the transverse trough.

Each side wall 12 of each trough is provided at its rear end with a recess 29 in its top edge. The recesses in the side walls of each trough are in the same vertical plane as the longitudinal center of the adjacent transverse trough 19 and each recess has its edges covered by a suitable wear strip 30.

Suspended in the transverse trough 19 of each of the troughs 11 is the horizontal or yoke portion 31 of a substantially U-shaped agitator which is indicated generally by the numeral 32. The upright arms 33 of each of the agitators 32 have formed integral therewith the supporting shafts 33' which pass through the adjacent recesses 29 in the side members of the troughs. Each shaft is formed to receive one end of a spring 34 the other end of which is secured in the manner shown to the adjacent upright 4 of the frame structure. In order to prevent the shafts 33 from accidentally disengaging from the recesses 29 in which they are placed there is pivotally attached to the top edge of each trough side wall 12 the keeper 35 which may be swung into position across the adjacent recess in the manner shown. The yoke portion 31 of each agitator is provided with the laterally directed fins 36 which serve to make the agitator more efficient. In order to prevent contact of the arms 33 of the agitators with the adjacent side walls 12 of the confining troughs, these arms are confined in an elongated yoke loop 37 which is secured in any suitable manner to the adjacent end wall.

Extending transversely of the water guides 23 of each trough adjacent the forward end thereof, is a bar 38 to which is attached a canvas float 39 which extends downwardly into the trough. The lower end of this float has secured thereacross a wood and/or metal bar 40 which serves to keep the float 39 in contact with the surface of the water and material passing through the trough.

In the operation of my machine the mineral carrying water is discharged into the uppermost of one of the troughs 11 and lateral oscillatory motion is given to all of the troughs by swinging the hanging beams 9 upon their supporting straps 7.

The mineral bearing water flows longitudinally through the first trough under the canvas float 39 which serves to force all of the lighter particles of minerals to the bottom of the stream of water where the same, if of the proper degree of fineness, pass through the fabric screen 20 to the bottom of the pan 17. These fine particles will be caught in the riffles 18 of the pan. The other particles of minerals flow to the rear end of the pan and are discharged into the transverse or cross trough 19. It will be seen that the agitators 32 are practically held against movement so that when the troughs are oscillated back and forth the fin carrying portions of these agitators will sweep lengthwise through the transverse trough in which they are positioned and will keep the mineral matter therein in a constant state of agitation. As the water, and material in suspension therein, flow through the cut down back wall of the top trough it will strike against the dash plate 22 of the next lower trough and will then flow through this trough in the same manner as described in connection with the first trough. The water guides 23 at the sides of the troughs keep down the formation of foam on the water and tend to make the same flow smoothly. As previously stated the canvas float forces to the bottom of the trough the fine particles of mineral matter which may rise to the top of the water as the same enters the trough.

Having thus described my invention, what I claim is:

1. In a mineral separating device, a trough designed to have mineral carrying water pass longitudinally therethrough and including a bottom, side walls and a front and rear wall, said rear wall being partially open to permit the discharge of water from the trough, riffles formed transversely in the bottom of the trough, a transverse trough formed adjacent the discharge end of the trough, and a fabric screen suspended in spaced relation to and over the bottom of the first mentioned trough and extending upwardly along its side and front edges over the adjacent walls of the first mentioned trough and further having its rear edge rigidly held and terminating adjacent said transverse trough.

2. In a mineral separating device, a trough designed to have mineral carrying water passed longitudinally therethrough and including bottom, side and front and rear walls, said rear wall having an opening through the central portion thereof to permit the water to discharge from the trough into a receiver therebeneath, riffles formed transversely of the bottom of the trough, a screen extending longitudinally of the trough bottom over said riffles, said trough at the rear end thereof having a transverse trough in the bottom thereof, said screen terminating at its rear end over said transverse trough, a body of

- flexible material disposed transversely of the trough and depending thereinto and engaging at its lower edge said screen, and inwardly and upwardly inclined water guides extending longitudinally of the side walls of the trough to prevent the boiling up of water passing therethrough. 5
3. In a mineral separating device, a trough designed to have mineral carrying water passed longitudinally therethrough, said trough including a bottom, side and end walls, one of said end walls having an opening formed therethrough to permit water to discharge from the trough, a relatively wide trough formed transversely of said bottom adjacent the open end wall, a plurality of 10 riffles formed transversely of the bottom of the trough, a fabric screen disposed above and in spaced relation to the bottom of the trough and extending from the closed end wall to the transverse trough, said screen having its side edges and the end edge adjacent the closed end wall turned upwardly and secured to the adjacent walls, a frame disposed transversely of the trough adjacent the transverse trough and having upright side members secured to the side walls of 15 the trough and a cross member disposed in the transverse trough, the other end edge of said screen being secured to said frame cross member, and a flexible body suspended into the trough from the upper portion thereof and having its lower edge shiftably held in close contact with 20 said screen, said flexible body operating to submerge mineral particles carried by the water passing through the trough. 25
4. In a mineral operating device, a trough designed to have mineral carrying water passed longitudinally therethrough and including a bottom a side and front and rear walls, said rear wall having the top edge cut down to permit the discharge of water from the trough, a transverse trough in said bottom adjacent the rear wall, said side walls having recesses formed therein adjacent the ends of the transverse trough, riffles formed transversely of said bottom, a screen overlying and spaced from said bottom and entirely 30 covering the same, said screen having one edge terminating over the transverse trough, an agi- 35
- tator comprising a substantially U shaped frame suspended in the trough with the yoke portion disposed in the transverse trough and having fins on said yoke portion, arms formed integral with the upright side members of the agitator frame and extended through the apertures in the side walls, and means for retaining said agitator in position while permitting movement thereof transversely of the trough. 40
5. In a mineral separating device, a trough designed to form one of a plurality and adapted to have mineral carrying water passed longitudinally therethrough, said trough including bottom, side and front and rear walls, said rear wall being open to permit water to pass therefrom, a screen in the bottom of said trough and spaced from the bottom, riffles disposed beneath said screen, upwardly and inwardly inclined bodies carried by said side walls and extending throughout the length thereof, a fabric body suspended from one edge into said trough and having its opposite or lower edge weighted to be maintained in close proximity to said screen, and a dash plate disposed at an upward and forward inclination against the front wall of the trough and extending a substantial distance above the same, to receive water flowing into the trough from an overlying body. 45
6. In a mineral separator, a trough structure designed to be oscillated in a path transversely to the flow of material therethrough, comprising an elongated body having a bottom, side walls, and an end wall, the other end of the body being open for the discharge of material therefrom, means associated with said trough whereby the finer particles of mineral matter being washed therethrough may be separated from the coarser particles, an agitator element suspended in the trough and having arms extending beyond the sides thereof, and resilient elements connected to 50 said arms to be secured to adjacent fixed bodies and operating to maintain the agitator element against material movement during the oscillation of the trough. 55
